UNITED STATES PATENT OFFICE.

NILS DAVID LEVIN, OF COLUMBUS, OHIO, ASSIGNOR TO THE JEFFREY MANUFACTURING COMPANY, A CORPORATION OF OHIO.

MINING-MACHINE.

1,244,871.

Specification of Letters Patent. Patented Oct. 30, 1917.

Original application filed September 30, 1907, Serial No. 395,061. Divided and this application filed September 20, 1911. Serial No. 650,334.

To all whom it may concern:

Be it known that I, NILS D. LEVIN, a citizen of the United States, residing at Columbus, in the county of Franklin and 5 State of Ohio, have invented certain new and useful Improvements in Mining-Machines, of which the following is a specification, reference being had therein to the accompanying drawing.

10 This invention relates to mining machines and particularly to those of the class in which the cutting apparatus and the power devices are moved bodily along the face of the material to be cut while the cutting work 15 is progressing.

One of the objects of the present improvements is to provide a flexible feeding device and a retarding or holding device adapted to be operated and controlled independently of each other, so that the flexible feeding device, (cable, chain or the like) is capable of being used independently of the retarding device to load and unload the machine and move it about on the floor of 25 the mine, while at the same time the feeding and retarding devices are adapted to co-operate with each other to automatically hold the machine to its work during the undercutting of the coal.

30 A further object of the invention is the provision in a machine of the character referred to of guiding or alining devices which operate by opposing a frictional resistance to the advance of the outer end of 35 the machine. A further object of the invention is the provision of frictional retarding devices such as last referred to adapted to automatically vary the frictional resistance to the advance of the outer end of the 40 machine in proportion to the resistance encountered by the cutters.

A further object is the provision in a machine of the character referred to of feeding and retarding devices adapted to permit 45 the machine in operation to occupy various angular positions in relation to the face of the coal, while the retarding devices are adapted to resist the angular swinging movement of the machine beyond a predetermined limit.

Another object of my invention is to provide means for adjusting the machine to different angular positions relative to horizontal planes, whereby it is capable of be-

ing adjusted either around horizontal lines 55 longitudinally of the machine or around horizontal lines which are transverse thereto, thus permitting cuts in the coal to be made in either of various planes and permitting the machine to be so manipulated that 60 obstructions in the path of the cutting apparatus can be escaped without stopping the cutting.

Referring now to the accompanying drawings,

Figure 1 is a plan view of a machine embodying my improvements, the top cover plate of the main frame being removed for the purpose of showing the mechanism under it.

Fig. 2 is a vertical section taken on the line 2—2 in Fig. 1.

Fig. 3 is a side elevation of the machine, the cutter chain being omitted.

Fig. 4 is an elevation of the outer end of 75 the machine.

Fig. 5 is a detailed plan view of the retarding device.

Fig. 6 is a diagrammatic plan view showing the machine in operation in the room of 80 a mine.

Referring in detail to the construction shown, the main structure of the machine comprises a box or casing part 1 having bottom, side and end plates and a removable 85 top plate 2. 3 is an interior frame structure shown as an integral casting, though not necessarily so formed, and rigidly secured as by bolts 4 to the casing part 1 of the frame. A cutter bar or frame 5 projects from the inner end of the main frame and carries a suitable endless cutter chain 6. This cutter chain passes around and is driven by a sprocket wheel 7 which is fast on the lower end of a shaft 8, which is rotatably mounted in the frame structure 3. 90

The machine can be driven by any suitable kind of motor, but I have indicated an electric motor 9 with a vertically arranged shaft. This is indicated conventionally, but the constructing engineer will understand that a motor of any suitable shape, size and power can be employed. 10 is a pinion carried by the motor shaft and this pinion meshes with a large gear wheel 11 which is sleeved upon the upper end of the shaft 8. 12 is a disk keyed to the shaft 8 and formed with a shoulder or tooth adapted to be en-

gaged by a pivoted hook or dog 13 carried by the gear 11. The dog 13 can be made of cast iron or other frangible material so that it will break in case the machine is over-loaded and thus serve as a safety device, preventing breakage of other more important parts of the machine.

14 is a winding drum which is fast on a vertical shaft 15, rotatably mounted in the 10 frame structure 3. 16 is a rope or cable having one end secured to the winding drum and adapted to be wound thereon, and extending thence through a suitable passage-way in the machine frame or bed, and the 15 other end being adapted to be made fast at a point on the front or advance side of the machine as by a jack 17. This winding drum is driven from the motor 9 by the following train of gearing. 18 is a ratchet 20 wheel fast on the shaft 15, and 19 is a swinging arm which carries a spring pressed pawl 20 adapted to engage the teeth of the ratchet wheel 18. A vertical shaft 21 which is rotatably mounted in the frame 3 carries 25 at its upper end a spur gear 22 which meshes with and is driven by a gear 23 fast on the hub of the gear 11. The shaft 21 also carries an eccentric 24 arranged to drive an eccentric rod 25 which extends 30 through the free end of the arm 19. The eccentric rod can be formed with a shoulder adapted to press against one side of the arm 19, and the end of the eccentric rod carries a nut 26 between which and the pawl arm 35 19 is arranged a coiled spring 27.

It will now be seen that when the motor is in operation its rotation is transmitted by gears 10 and 11 to the shaft 8 thence by gears 22 and 23 to the shaft 21. The rotation of the shaft 21 causes the reciprocation of the eccentric rod 25 and this reciprocatory movement of the rod causes the oscillatory swinging of the pawl arm 19. It will be seen that the force which causes the 45 working stroke of the pawl arm 19 is transmitted through the spring 27 and thus the amount of rotation of the ratchet wheel and winding drum and the consequent advance of the machine incident to the winding in 50 of the feeding cable 16, is automatically proportioned to the resistance met by the cutters. That is, when the coal is hard or when hard foreign substances therein are encountered so that the reaction on the cutter frame is great, the transmission spring 55 27 is correspondingly compressed and the amount of the forward feed of the machine correspondingly diminished so that the cutters are given opportunity to cut their way 60 through the hard spot. When this has been accomplished and softer material is encountered, the compressing of the spring during the working stroke of the pawl arm will be less and the machine will then be fed forward at a correspondingly faster speed. It

will be understood that suitable means, such, for example, as a relatively stationary pawl, is to be provided to normally prevent retrograde movement of the winding drum. Such a pawl is indicated at 18 and can be supported from the under side of the upper plate 3* of the frame structure 3.

When the machine is drawn forward by the cable 16 along the face of the coal, the outer end of the main frame tends to swing 75 forward on account of the reaction of the coal against the cutters. To oppose this tendency and hold the machine at a suitable angle to the face of the coal as the undercutting proceeds, I provide the following 80 devices. 28 is a rod, beam or rail, which may, for example, be an ordinary I-beam of suitable weight and dimensions and which is adapted to be disposed on the floor of the mine adjacent the outer end of the 85 machine and secured against endwise movement. Any suitable means such as a jack 29 can be employed to thus secure the rail. It is not essential that the rail be held against lateral movement so long as it is 90 not free to move in the machine's general direction of movement. Indeed, in some cases, I prefer to secure the rail at one point only so that it will be free to swing somewhat and not interfere with the free working 95 of the machine. This rod or rail can be of any suitable shape in cross section and of any suitable length. Rails or rods for meeting a more or less similar purpose have been heretofore known in the art, and 100 they have been made sometimes flat, sometimes circular in section, sometimes in long sections, and in others, of shorter lengths. And I wish it to be understood that any of the known devices of this class can be 105 adapted for use in conjunction with my mechanism. I prefer to employ rails or bars of suitable lengths of the standard cross sectional shape of the track rails used in mining work, so that they can be readily 110 obtained from the general stock of materials at the mine and can be quickly replaced in the event that renewal is required. On the outer end of the frame 1 of the machine is secured or formed a bracket 30 which is 115 formed on its under side with jaws adapted to pass around the upper flange or head of the rail and engage the web thereof. The distance between the jaws of the bracket 30 is greater than the thickness of the web of 120 the rail, and the faces of the jaws are formed parallel to each other. Thus the machine can swing or angle to a limited extent without the jaws engaging the rail, but any swinging of the machine beyond 125 such limitations is prevented or opposed by a clutch-like engagement of the jaws with the web of the rail. In the construction shown, the faces of the clutch jaws are disposed so as to clutch the rail when the longi- 130

tudinal axis of the machine is at substantially right angles to the face of the coal and the rail and yet so as to permit the inner end of the machine to be angled forward to various positions as may be desired to meet various conditions of cutting. The interaction of the bracket 30 and rail 28 will be understood from an inspection of Figs. 3, 5 and 6. Referring to Fig. 5, it will be seen that the corners 30^a and 30^b of the bracket jaws clutch the rail when the outer end of the machine swings forward to the limiting position, and that the outer end of the machine can swing rearward (or the inner end forward), as in Fig. 6, to a considerable extent before the corners 30^a and 30^b will come into clutching engagement with the rail. This capacity of the machine for angling is one of the characterizing features of my invention, as will be pointed out more fully in connection with the operation of the machine.

If a section of track rail is used as the rod 28 and if the bracket 30 is formed as herein shown, it will be understood that the parts of the retarding mechanism can readily be assembled by passing the rod or rail 28 endwise through the bracket. The passageway for the rail through the bracket should be sufficiently wide to permit the machine to be angled, as set forth, above, and the bracket should have suitable vertical dimensions to permit the required vertical adjustment of the machine by means of the devices to be described. If a bar of the section of the track rail be employed, and if the jaws of the bracket 30 are spaced as herein shown, the fitting of the parts of the retarding mechanism can be readily accomplished by first passing the rail a short distance endwise through the bracket. But, in this respect also, I do not wish to be limited to any exact details so long as the essential features of this part of the invention are maintained.

The passageway for the rail through the bracket should be sufficiently wide to permit the machine to be angled, within limits, in relation to the bar or rail so as to get a strong bite of the bracket jaws upon it. It should also have sufficient vertical dimensions to permit the required vertical adjustment of the machine by means of the devices to be described.

It will be seen that the clamping part on the machine, is, at its working points, very short, that is to say the jaws of the bracket are short in relation to the length of the part which exerts leverage upon them, which in this case would be measured on the line from these jaws to the cutting apparatus. Consequently, the clamping bite or binding action is powerful and quickly becomes effective as soon as the machine moves any material distance out of its predeter-

mined angular relationship to the coal face. Under normal circumstances, and while the machine is in the predetermined angular position, the clamp or clutch part on the machine is practically disengaged entirely from the elongated stationary element of the retarder. This retarding mechanism is quite different from those heretofore proposed which had elongated base lines of union between the machine and the rail element, along which lines there were a series of rotating anti-friction rollers. In those, the proposition was to use the rail and the outer end of the machine as an alining device, and the counterpart elements were normally retained constantly in close engagement over the long base of connection. In my construction, the purpose is not to maintain a constantly rigid connection between the counterpart elements of the retarder; the rear end of the machine being normally free or disengaged while in its proper working angle, but instantly caught and checked against any tendency to move beyond a certain angular limit.

The machine can be supported from the floor of the mine in any suitable manner but I have shown a shoe 31 under the inner end of the machine, and at the outer end of the machine I provide a pair of rollers 32-32 which are adapted to ride upon the rail 28. These rollers are mounted on a bar 33 which in turn is mounted upon a block 34 which is slidably mounted in guides 35 on the machine frame. A hand screw 36, which is swiveled to the block 34 and threaded through a bracket 37 on the frame serves to adjust the block 34 up and down, so as to lower and raise the outer end of the machine. 38 is a hand screw threaded through a bracket 39 on the frame of the machine and having a loose engagement with the bar 33. By turning the hand screw 38 up and down, the machine can be tipped around a longitudinal axis so as to direct the cutters upward or downward.

The operation of my improved mining machine will be readily understood from the foregoing description. When the machine is brought into a room where the coal is to be undercut, it is first placed at the face of the coal near one of the ribs or side walls where the entering or sumping cut is to be made. It has been customary in machines of this character to make the sumping cut by anchoring the feed chain or cable at a point adjacent the face of the coal and near the cutter frame so that the rotation of the winding drum will cause the cutter frame to be forced endwise against the coal, the main frame of the machine being in the meantime guided and held against swinging.

After the sumping cut has been made, the feed cable is carried along the face and anchored as indicated in Fig. 6. The I beam

or rail is then slipped through the jaws of the retarding bracket and is then secured by one or more jacks upon the floor of the mine. On the motor now being started, the cutters 5 are driven and the winding drum 14 turned so as to draw in upon the feed cable 16. As the machine advances along the face of the coal, the outer end of the frame tends ordinarily to swing forward in advance of the 10 inner end because of the resistance which the coal offers to the cutters. But when the outer end of the frame swings forward to a certain point, the jaws of the bracket 30 clutch the rail 28 and by the frictional resistance thus produced counteract the tendency of the outer end of the machine to swing forward. The greater the resistance which the coal offers to the cutters and the greater the consequent tendency of the outer 15 end of the machine to swing forward, the greater is the frictional resistance which results and thus automatically the longitudinal axis of the machine is maintained at substantially the same angle to the face of 20 the coal as the undercutting proceeds.

In the cutting of coal, impurities are frequently encountered which constitute serious obstacles, that is to say, obstacles which it is not practical to cut through because of their 25 extreme hardness. In such cases if the vertical dimensions of the obstacles are not great, it may be possible to direct the cutters over or under the obstruction, and such a manipulation of my improved machine is 30 facilitated by the provision of the adjusting screws 36 and 38 by means of which the outer end of the machine can be bodily raised and lowered and by means of which the machine can be tipped around its longitudinal axis so 35 as to direct the cutters upward or downward. Furthermore, by reason of the capacity of my improved machine for angling forward and backward in the manner previously described, the cutters can be caused to attack 40 the coal at various angles. Sometimes an obstruction in the form of a relatively small sulfur ball is encountered and by inclining the inner end of the machine forward, as indicated in Fig. 6, it is possible to cut more or 45 less back of the sulfur ball and thus make it easier for the cutters to loosen and dislodge the ball so that it can be removed from the kerf. When such handling of the machine is 50 desirable, the cutters can be swung to the desired angle through the action of the feed devices by setting a jack or the like in front of the outer end of the machine so as to 55 stop the advance of said outer end, while the inner end is swung forward. Such angling 60 of the machine forward or backward—and it may be accomplished in a variety of ways as will be understood by practical machine operators—is rendered possible by reason 65 of the peculiar coöperative relation between 70 the parts of the retarding mechanism.

It will be seen that the clamping part on the machine, is, at its working points, very short, that is to say, the jaws of the bracket are short in relation to the length of the part which exerts leverage upon them, which 75 in this case would be measured on the line from these jaws to the cutting apparatus. Consequently, the clamping bite or binding action of the jaws is very powerful. This retarding mechanism is quite different from 80 those heretofore proposed which had elongated base lines of union between the machine and the rail element, along which lines there were a series of rotating anti-friction rollers. In those, the proposition 85 was to use the rail and the outer end of the machine as an alining device, and the counterpart elements were normally retained constantly in close engagement over the long base of connection. In my construction, the purpose is not to maintain a 90 constantly rigid connection between the counterpart elements of the retarder, the outer end of the machine, on the contrary, being free to take a variety of positions relative to the inner end, but being instantly caught and checked against any tendency to move beyond a certain angular limit.

The present application is a division of my earlier application, Ser. No. 395,061 filed 95 September 30, 1907.

What I claim is:

1. In a mining machine, the combination of a main frame arranged to swing horizontally forward and back when in operation, 100 power driven cutting apparatus projecting from the inner end thereof, power devices for feeding the machine along the face of the coal, and means for retarding the outer end of the machine comprising a stationary 105 part secured against movement in the direction of the machine's advance and a companion element on the machine arranged to be moved by the frame, when swinging as aforesaid, toward and from a position where 110 it tends to rigidly engage said stationary part, but to loosely engage with the latter when the frame is at a predetermined angle.

2. In a mining machine, the combination of a main frame arranged to swing horizontally forward and back when in operation, power driven cutting apparatus projecting from the inner end of the main frame, a flexible draft device acting on the inner end of the main frame to propel the machine 120 along the face of the coal, and means acting on the outer end of the machine for limiting its swinging movement, said last mentioned means comprising an elongated device secured against movement in the direction of 125 the machine's advance, and a device on the machine engaging with said elongated device and arranged to be moved when the frame swings as aforesaid, to and from a position where it tends to engage rigidly 130

with said device but adapted to move along the latter freely when the frame is at a predetermined angle.

3. In a mining machine, the combination 5 of a main frame arranged to swing horizontally forward and back when in operation, power driven cutting apparatus projecting from the inner end thereof, power devices for feeding the machine along the face of 10 the coal, and means for retarding the outer end of the machine comprising a part secured against movement in the direction of the machine's advance, and coöperating means on the machine arranged to loosely 15 engage said stationary part when the frame is in a predetermined angular position and to be moved by the frame, when it is swinging, to and from a position where it tends to rigidly engage the said stationary part.
4. In a mining machine, the combination 20 of a main frame arranged to swing horizontally forward and back when in operation, power driven cutting apparatus projecting from the inner end thereof, power devices 25 for feeding the machine along the face of the coal adapted to permit the machine to swing as aforesaid to various angular positions in relation to the coal face, and means for retarding the outer end of the machine 30 comprising a rod extending approximately parallel to the face of the coal adjacent the outer end of the machine, means for securing the rod against movement in the direction of the machine's advance, and a clutch- 35 like device on the machine adapted to freely slide along the rod when the machine is in a predetermined angular position and to be moved by the frame, when swinging as aforesaid, to and from a position where it 40 tends to rigidly engage said rod.
5. In a mining machine, the combination 45 of a main frame, power driven cutting apparatus projecting from the inner end thereof, power devices for feeding the machine along the face of the coal, means for retarding the outer end of the machine comprising a rail secured against movement in the direction

of the machine's movement, a friction device on the machine adapted to engage said rail, and means for directing the cutting apparatus up or down comprising a plurality of wheels carried by the machine frame in position to ride upon the said rail, and means for adjusting one of said wheels upward and downward relative to the machine. 50

6. The combination of a main frame arranged to swing horizontally forward and back when in operation, a forwardly projecting cutter apparatus, a means for feeding the frame along the face of the coal, a 60 retarding means comprising a stationary element approximately parallel to the path of the machine, a companion element on the machine adapted to move longitudinally of the stationary retarding element when the 65 machine is in a predetermined angular position and to be moved by the frame, when the latter swings, as aforesaid, to and from a position where it tends to rigidly engage the stationary element. 70

7. In a mining machine, the combination of a main frame arranged to swing horizontally forward and back when in operation, power driven cutting apparatus projecting from the inner end thereof, power devices 75 for feeding the machine along the face of the coal, means for retarding the outer end of the machine comprising a rail secured against movement longitudinally, an element carried by the frame and engaging 80 said rail and having limited vertical movement, said element being adapted to permit horizontal swinging of the main frame independently of the rail, a bar vertically adjustable on the frame, wheels carried thereby and in engagement with the upper surface of the rail, and means for vertically adjusting one end of the said bar. 85

In testimony whereof I affix my signature, in presence of two witnesses.
